Patented Feb. 13, 1912.

UNITED STATES PATENT OFFICE.

DAVIS SHEEN, OF RUDD, TEXAS.

WINDMILL AND ENGINE COUPLING.

1,017,021.

Specification of Letters Patent. Patented Feb. 13, 1912.

Application filed June 26, 1911. Serial No. 635,498.

To all whom it may concern:

Be it known that I, DAVIS SHEEN, a citizen of the United States, residing at Rudd, in the county of Schleicher and State of Texas, have invented a new and useful Windmill and Engine Coupling, of which the following is a specification.

The invention relates to a coupling for connecting the piston or plunger of a pump with either a windmill or an engine, or analogous motor.

The object of the present invention is to improve the construction of couplings, and to provide a simple, efficient and comparatively inexpensive windmill and engine coupling, adapted to be easily operated to connect the piston or plunger of a pump with either the pitman of an engine, or the pump rod of a windmill.

With these and other objects in view, the invention consists in the construction and novel combination of parts hereinafter fully described, illustrated in the accompanying drawing, and pointed out in the claims hereto appended; it being understood that various changes in the form, proportion, size and minor details of construction, within the scope of the claims, may be resorted to without departing from the spirit or sacrificing any of the advantages of the invention.

In the drawing:—Figure 1 is a side elevation of a coupling, constructed in accordance with this invention, a portion of the tower of the windmill and the well being in section. Fig. 2 is an enlarged vertical sectional view of the coupling. Fig. 3 is a similar view on the line 3—3 of Fig. 2. Fig. 4 is a horizontal sectional view on the line 4—4 of Fig. 2. Fig. 5 is a similar view on the line 5—5 of Fig. 2. Fig. 6 is a horizontal sectional view on the line 6—6 of Fig. 2.

Like numerals of reference designate corresponding parts in all the figures of the drawing.

In the accompanying drawing in which is illustrated the preferred embodiment of the invention, 1 designates an upright casing composed of side plates spaced apart by a central vertical bar or piece 2, which co-operates with the side plates to form opposite guides or ways 3 for the reception of vertically reciprocable bars 4 and 5, which are retained in the grooves or ways 3 by means of an approximately U-shaped cuff 6. The cuff 6 is composed of opposite sides and

a connecting portion, the sides being arranged at the side edges of the plates of the casing and extending across the grooves or ways thereof, as clearly shown in Figs. 3 and 5 of the drawing. The outer terminals of the sides of the cuff project beyond the casing and are connected by a bolt 7. The casing instead of being made of separate pieces may be, of course, constructed in any other desired manner. The spaced side plates of the casing are secured to the centrally arranged spacing bar or piece 2 by means of lower bolts 8, which also attach the casing to the upper end of the piston or plunger 9 of a pump 10. The pump 10 may be of any preferred construction, and the cuff 6 is secured to the casing by upper horizontal bolts 11 and 12, which also connect the side plates of the casing. The bolt 12 pierces the upper end of the spacing bar or piece 2, which terminates short of the upper ends of the side plates of the casing to provide a recess 13 for the reception of the lower portions of approximately triangular plates or members 14, which are pivoted in the recess 13 by the bolt 11. The oscillatory plates or members 14, which taper downwardly, as clearly illustrated in Figs. 1 and 2 of the drawing, form an oscillatory support for a pair of opposite catches 15 and 16 for connecting the casing with either of the reciprocatory bars 4 and 5. Each catch consists of a pair of parallel sides or links 17, connected at their inner ends with the plates 14 by an inner pivot 18 and having their outer ends connected by an outer transverse pin 19. The reciprocatory bars 4 and 5, which pass through the catches, as clearly illustrated in Fig. 5 of the drawing, are each provided with inner and outer notches 20 and 21, arranged at different elevations and adapted to be engaged by the catches when the same are in an inclined position, as illustrated in Figs. 1 and 2 of the drawing. The inner pivot pins 18, which are located opposite the lower notches or recesses 20, operate in the space between the vertically reciprocable bars 4 and 5, and the plates 14 are located at the side faces of the same. The inner or lower notch or recess 20 has upper and lower approximately horizontal walls, and the upper notch 21 has a lower approximately horizontal wall and an upper inclined wall 22. The inner pin 18 is engaged by the upper wall of the lower notch or recess of its co-acting reciprocable bar

on the down stroke, and the lower wall of the upper notch or recess of such bar engages the outer pin of the catch on the up stroke.

5 When the outer pin or engaging portion of the catch 15 is swung into the notch or recess 21 of the reciprocatable bar 4, the latter in its upward movement will lift the catch 15 and draw the inner pivot thereof 10 into the inner recess or notch 20. This movement oscillates the supporting plates 14 and withdraws the inner pivot of the other catch 16 from the lower inner notch or recess of the reciprocatable bar 5. The 15 lifting movement of the catch 15 draws the casing in the direction of the actuating bar 4 and there is comparatively little friction in the operation of the coupling. When the outer pin or engaging portion of the catch 20 20 16 is swung into the upper notch of the reciprocatable bar 5, the latter in its upward movement will draw the inner pin or pivot of the catch 16 into the lower inner notch of the recess 20 of the bar 5, and withdraw the 25 pivot of the other catch from the lower notch or recess 20 of the bar 4, and the continued upward movement of the bar 5 will cause the catch 15 to swing outwardly and downwardly by gravity and clear itself automatically of its engagement with the bar 4. When the catch swings outwardly and downwardly it rests upon the upper edge of the cuff, and the outer engaging portion or pin lies beyond the co-acting reciprocatory 30 35 bar, and there is no liability of the catch becoming accidentally engaged with the same.

The vertically reciprocatable bar 4 is designed to be connected at its upper end with the pump rod of a windmill and to be actuated by the same, or it may constitute a portion of the pump rod, and it preferably passes through an opening 23 in a horizontal guide bar 24, suitably secured at its ends to the tower 25 of the windmill, and 40 45 equipped with approximately L-shaped metallic plates 26, having spaced projecting flanges receiving the bar 4 between them and forming wear plates for protecting the bar 24. When the catch 15 of the coupling is 50 55 engaged with the bar 4, the piston rod or plunger 9 of the pump will be actuated by the windmill. The windmill actuated bar 4 also passes through a guide consisting of spaced plates or pieces 27, secured by bolts 55 60 65 28, or other suitable fastening devices to the opposite faces of the upper end of the reciprocatory bar 5. The sides or plates 27 of the guide are spaced apart by the upper end of the bar 5, and they extend in opposite 60 65 70 directions therefrom, and they are also connected by a central horizontal bolt 29, upon which an anti-friction roller 30 is mounted. The anti-friction roller is arranged in the space between the bars 4 and 5, and it is adapted to bear against the latter when the 65 70 75 80 85 90 95 100 105 110 115 120 125 130

bar 5 is connected with the coupling. The projecting terminals 31 of the sides or plates 27 are pivotally connected by a horizontal transverse bolt 32 with the upper end of an upright pitman 33. The pitman 33 is connected at its lower end with a crank or wrist pin 34 of an engine 35 or analogous motor, and its upper end 36 is bifurcated or forked to straddle the projecting terminals 31 of the sides or plates 27 of the guide, a spacing sleeve 37 being preferably mounted on the bolt 32 and interposed between the projecting ends 31. The engine is adapted to actuate the pump and is designed for use during the summer season and at other times when there is comparatively little wind. At other seasons when there is ample wind for operating the pump through the windmill and there is no occasion for frequently coupling the pump rod from one of the bars 4 and 5 to the other, the pitman may be disconnected from the guide, and the plates 27 of the latter may be secured to the bar 4 by means of a bolt or pin, suitable perforations 38 and 39 in the bar 4 and the plates 27 being provided for this purpose. This will cause the bars 4 and 5 to move in unison and will relieve the coupling of wear. However, at seasons of the year where it is desirable to use the coupling frequently to change the power, the pitman of the engine will be pivoted to the plates 27 and the change will be effected by means of the catches of the coupling.

Although a straight pitman connection 100 between the plates 27 and the engine is illustrated in the accompanying drawing, it will be readily understood that any suitable means may be employed for transmitting motion from the engine or other motor to the reciprocatory bar 5.

Having thus fully described my invention, what I claim as new and desire to secure by Letters Patent, is:—

1. A device of the class described including a casing designed to be connected with the plunger or piston rod of a pump, reciprocatory bars slidably arranged in the casing, one of the bars being provided with means for connecting it with the pump rod of a windmill, means for connecting the other bar with an engine or motor, a guide spaced from the casing and mounted on one of the reciprocatory bars and receiving the other reciprocatory bar and provided with an antifriction device arranged to bear against the same, and means for connecting either of the said reciprocatory bars with the casing.

2. A device of the class described including a casing designed to be connected with the plunger or piston rod of a pump, reciprocatory bars slidably mounted in the casing, one of the reciprocatory bars being provided with means for connecting it with a

windmill, a guide spaced from the casing and secured to the other reciprocatory bar and slidably receiving the first-mentioned reciprocatory bar, a pitman pivoted to the 5 guide and adapted to be connected with the crank or wrist pin of an engine, and means for connecting either of the reciprocatory bars with the casing.

3. A device of the class described including a casing designed to be connected with the plunger or piston rod of a pump, reciprocatory bars slidably arranged in the casing, one of the reciprocatory bars being provided with means for connecting it with 10 a windmill, a guide consisting of plates secured to the other reciprocatory bar and extending therefrom in opposite directions and arranged at opposite sides of the first-mentioned reciprocatory bar, an anti-friction 15 roller mounted between the guide plates and also arranged between the reciprocatory bars and forming a bearing for the said first-mentioned reciprocatory bar, and means for connecting the guide with the engine or 20 motor.

4. A device of the class described including a casing having means for connecting it with the plunger or piston rod of a pump, reciprocatory bars slidably arranged in the 25 casing, one of the bars being provided with means for connecting it with the pump rod of a windmill, means for connecting the other bar with an engine or motor, a pair of independently movable catches, one for 30 each bar, each catch engaging the bar at opposite sides, and means for connecting the catches with each other and with the casing, whereby when one catch is engaged with one of the reciprocatory bars such engagement will cause the other catch to be 35 automatically released from the other bar.

5. A device of the class described including a casing, spaced reciprocatory bars slidably arranged in the casing and provided at 40 their inner and outer edges with notches arranged at different elevations, and a pair of catches connected with the casing and each provided with inner and outer portions

arranged to simultaneously engage the inner and outer notches of the reciprocatory bars, 50 whereby either one of the same may be coupled to the casing.

6. A device of the class described including a casing, spaced reciprocatory bars slidably arranged in the casing and provided with inner 55 and outer notches, catches each having inner and outer portions for simultaneous engagement with the inner and outer notches of the said bars, and means for connecting the catches with the casing and with each 60 other, whereby when one of the catches is engaged with its co-acting bar it will automatically disengage the other catch.

7. A device of the class described including a casing, reciprocatory bars slidably arranged in the casing and provided with inner and outer notches located at different elevations, an oscillatory support pivotally connected with the casing, and opposite 65 catches consisting of pairs of links, and inner and outer connecting portions arranged to engage the notches of the reciprocatory bars, the inner connecting portions forming pivots and connecting the links to the oscillatory support.

8. A device of the class described including a casing, spaced reciprocatory bars slidably arranged in the casing, an oscillatory support composed of spaced plates arranged at the opposite faces of the reciprocatory 80 bars and pivotally connected with the casing, and opposite catches consisting of links located at the opposite faces of the said bars, and inner and outer pins connecting the links and arranged at the inner and outer 85 edges of the bars and adapted to engage the same, the inner pins piercing the said plates and pivoting the catches to the oscillatory support.

In testimony, that I claim the foregoing 90 as my own, I have hereto affixed my signature in the presence of two witnesses.

DAVIS SHEEN.
